(57) **CLAIM**

The ornamental design for an indoor wall for the built-in home appliances, as shown and described.

DESCRIPTION

FIG. 1 is a front perspective view of the indoor wall for the built-in home appliances showing our new design;

FIG. 2 is a front view thereof;

FIG. 3 is a rear view thereof;

FIG. 4 is a left side view thereof where the right side view is a mirror image;

FIG. 5 is a top plan view thereof where the bottom plan view is a mirror image; and,

FIG. 6 is a reference view showing the state of use that the clothes management apparatus has been separated from the frame.

The broken lines depict portions of the indoor wall for the built-in home appliances that form no part of the claimed design.
